UNITED STATES PATENT OFFICE.

HARRY L. WILSON, OF BOSTON, MASSACHUSETTS, ASSIGNOR OF ONE-HALF TO HUGH SHEPHERD, OF BOSTON, MASSACHUSETTS.

EASEL-SUPPORT.

SPECIFICATION forming part of Letters Patent No. 773,177, dated October 25, 1904.

Application filed September 26, 1903. Serial No. 174,834. (No model.)

To all whom it may concern:

Be it known that I, HARRY L. WILSON, of Boston, in the county of Suffolk and State of Massachusetts, have invented certain new and 5 useful Improvements in Easel-Supports, of which the following is a specification.

This invention relates to an easel-support for exhibiting cards or other articles; and its object is to provide a support adapted to be 10 made out of a single sheet of cardboard or other material and which shall possess maximum stability, be capable of unfolding into flat form, so as to pack in a small space, and be held together without the use of separate 15 fastening devices, such as staples or rivets.

Of the accompanying drawings, Figure 1 is 20 a plan view of my improved easel-support in a flat or unfolded state. Fig. 2 is a side elevation thereof in operative form. Fig. 3 is a 25 perspective view.

The same reference characters indicate the same parts in all the figures.

The easel-support comprises a front plate or section composed of upper and lower portions *a a*, separated by a recess, as seen in 25 Fig. 2; side wings, flaps, or standards *b b*, hinged to said upper and lower portions of the plate *a a* along the broken lines *d d* in Fig. 1, and a standard locking-tongue *c*, 30 hinged on the horizontal broken line *f*, Fig. 1, to the upper edge of the lower portion of the front plate *a a* and extending backwardly, as seen in Fig. 2, to engage the edges of the standards *b b*. The tongue *c* is formed with 35 parallel slits *e e*, which receive the edges of the standards *b b* and hold the latter in parallel relation at right angles to the front plate *a a*, the margins of the slits *e e* acting as two pairs of abutments or jaws, which straddle the standard *b b*. The plane of the lower edges of the standards *b b* is inclined to the front plate *a a*, the latter being thereby inclined to the base-plane of the easel-support, as seen in Figs. 2 and 3.

45 This device is preferably made from a single sheet of material, such as cardboard, and in that event the standards *b b* and locking-

tongue *c* are pivotally connected with the front plate *a a* by crease-hinges, as will be evident. The tongue *c* and the upper portion 50 of the lower half of plate *a a* are formed by cutting the C-shaped cleft *g* in the flat piece of material seen in Fig. 1. When, therefore, the standards *b b* are bent back along their hinge-lines and the tongue *c* is bent back to 55 engage the said standards, a gap or recess is formed between the upper and lower portions of the front plate *a a* and the front edge of each of the standards *b b* is a straight line interrupted by a reentrant-line. 60

In the operation of this device it is intended to paste or otherwise secure the front plate *a a* to the back of the card or other device to be displayed. The cards with these easel-supports attached may then be packed close together, since the parts of the easel-support will all unfold into the same plane while attached to the card. 65

The construction above described may be varied considerably without departing from 70 the idea contained in my invention.

I claim—

1. A card-exhibiting easel-support comprising a front plate inclined to the base-plane of the easel-support, a side standard hinged to 75 said plate along an upright edge of the latter, and a hinged locking-tongue in a plane transverse to said standard formed with a slit which receives said standard to lock the latter against pivotal movement. 80

2. A card-exhibiting easel-support comprising a front plate inclined to the base-plane of the easel-support, side standards hinged thereto, and a hinged locking-tongue having two sets of jaws straddling the respective standards for maintaining the latter in a fixed angular relation to the front plate. 85

3. A card-exhibiting easel-support comprising a front plate inclined to the base-plane of the easel-support, side standards crease-hinged 90 thereto, and a crease-hinged locking-tongue having two sets of jaws straddling the respective standards, all of said parts being integral portions of the same sheet of material.

4. A card-exhibiting easel-support comprising a front plate inclined to the base-plane of the easel - support, parallel side standards crease-hinged to said plate, and a backwardly-extending standard locking-tongue crease-hinged to the plate above said base-plane on a substantially horizontal axis and formed with parallel slits which receive the edges of

the standards, all of said parts being integral portions of the same sheet of material.

In testimony whereof I have affixed my signature in presence of two witnesses.

HARRY L. WILSON.
